UNITED STATES PATENT OFFICE.

ALBERT COLLET, OF PARIS, FRANCE.

BORING-MACHINE.

No. 844,099.

Specification of Letters Patent.

Patented Feb. 12, 1907.

Application filed June 30, 1905. Serial No. 267,864.

To all whom it may concern:

Be it known that I, ALBERT COLLET, a citizen of the Republic of France, residing in Paris, France, have invented certain new and useful Improvements in Boring-Machines, of which the following is a specification.

This invention relates to a portable boring-machine—that is to say, a machine which can be easily displaced to bring it over the pieces of wood to be bored and which is particularly suitable for the construction of railway-tracks, the boring apparatus being capable of being brought just above the sleeper or tie placed upon the ballast in which it is desired to bore holes serving to receive screws which fix the rails in place.

The machine is fixed by its base upon the rail and has the same inclination as the rail, so that the boring-tool is naturally directed parallel with the transverse axis of the web of the rail, thus forming the hole for the screw in the sleeper in the exact direction required for the head of the screw to quite normally bear upon the foot of the rail. In the case of chaired tracks the machine is vertical, the screws being in this case driven normally to the sleeper. This movable apparatus is arranged so as to be mechanically actuated by means of a suitable motor. In this machine the boring-tool has its point or end guided by a ring adjusted in a centering device, which insures the exact boring of the hole in the sleeper.

In the accompanying drawings, Figure 1 is a side elevation of a machine for boring railway-sleepers constructed according to my invention. Fig. 2 is an end view of the same, partly in section. Fig. 3 is a longitudinal section drawn to a larger scale and clearly showing the arrangement of the internal parts. Fig. 4 is a vertical transverse section taken through the joint of the fork on the shaft of the boring-tool holder. Fig. 5 is a transverse section on the line M M, Fig. 3.

The machine has a closed casing *a*, inside which are arranged two bevel-pinions *b* *c*, which are always in engagement. The pinion *b* is keyed upon a horizontal shaft *d*, terminated by a squared head *e*, which by means of a sleeve *f* allows of coupling the shaft *d* with the driving-shaft *g*, actuated by suitable motive power. The other pinion *c* is keyed upon a vertical sleeve *h*, which can turn in bearings *i* *i'* and within which the

tool-shaft *j* *j'* can be displaced. The latter is of square section at the upper part *j'* in order to slide in the sleeve *h*, and it is of round section at the lower part *j*, which terminates in the boring-bit holder.

60

The casing *a* is held by a frame *k*, fixed at the end of the tubes *l* *l* of a support which is mounted upon wheels in order to allow of easily moving the apparatus from place to place. These two tubes form an oblique or 65 horizontal plane for giving either a slightly-deviating direction to the apparatus itself, as indicated in Fig. 2, or a perfectly vertical direction.

The apparatus must deviate from the vertical when it is required to be used for boring sleepers for certain forms of tracks in order that the screws may have their axes normal to the foot of the rail, which is oblique. When, however, it is required to bore sleepers for 75 tracks with double-headed rails, the boring apparatus occupies a vertical position, the tubes *l* *l* being then horizontal, the obliquity of the rail being obtained in this case by the foot of the chair and the screws being vertical.

The machine is reversible upon the tubes *l* *l* in order to have the levers *s* and *3* *3*, hereinafter referred to, in front of the machine.

At the base of the casing *a* is fixed a tube 85 *m*, within which passes the lower part *j* of the vertical shaft, which turns in bearings *n* *n'*, fixed on a sleeve *o*, (shown in Fig. 3,) which can be longitudinally displaced in the outer tube *m*. This sleeve *o* serves to guide the 90 tool-shaft *j* in its vertical movement. To this end the tube *m* is provided with two elongated openings *p*, through which pass two trunnions *q*, with which the sleeve *o* is provided. These trunnions are engaged in eyes 95 made in the branches of the fork *r*, fixed to a hand-lever *s*. The ends of the fork *r* are connected by joints to small connecting-rods *t*, which are themselves jointed to a shaft *t'*, forming a tie-bar for the frame *k*. A spiral 100 spring *u*, fixed to a rod *v* between the two branches of the fork *r* and to the casing *a*, tends to keep the fork *r* in its elevated position.

The lower end of the tool-shaft *j* is screw-threaded to receive the tool-holder consisting of a screw-threaded socket *w*, screwed on the shaft *j* and which bears through the medium of a ball-bearing against the lower bearing *n'*.

To the lower part of the tube *m* is connect- 110

ed a casing x , which is stayed by means of four legs k' , fixed to the frame k . This casing x is formed with a horizontal projecting portion x' , which guides two pairs of jaws $l l$. These pairs of jaws, one seen at each side of the boring-tool, are clearly shown in Fig. 2. It is necessary to thus have two pairs of jaws in order that the shaft of the boring-machine may be brought to the right or left hand side of the rail for the purpose of boring in the sleepers holes for bolts on either side of the foot of the rail or of the chair. The jaws of each pair play into a slot formed in the lower part of a guide-socket in x' , and the parts which are within the said guide-socket are provided, respectively, with right and left screw-threads, so as to receive a bar 2, provided with correspondingly-opposite threads. This bar 2 is terminated on the outside by a square head y , on which is mounted a notched or serrated washer z in engagement with corresponding notches or serrations in the boss z' of a lever 3, the said boss z' being loose upon the square head y —that is to say, its central opening has a diameter equal to the diagonal of the square of y . A nut e' screwed over the threaded end of the bar 2 insures the engagement of the notches or serrations z and z' , the washer z upon the bar 2 being secured by the square y .

By unscrewing the nut e' the notched or serrated washer z can be disengaged from the socket z' of the lever 3. By then turning the washer z in one direction or the other, and consequently moving the bar 2 by the square y , the two jaws $l l$, mounted on the bar 2, are moved toward or away from each other. The distance apart of the jaws $l l$ can be thus easily adjusted to enable them to grip any kind of rail. When the distance apart of the jaws $l l$ has thus been adjusted to suit the type of rail of the track to be laid, the washer z and the socket z' are again engaged and the nut e' is screwed up. Now by acting upon the lever 3 and causing it to only move a short distance the final movement of the jaws toward each other against the sides of the head of the rail can be effected, owing to the very steep pitch of the thread of the screw on the bar 2.

To keep the lever 3 in a suitable position in order that the jaws $l l$ may remain firmly applied against the sides of the rail, I provide a sector 5, which guides the lever 3. It is fixed to the frame k and has a sleeve 16 mounted upon the tube l . This lever 3 should be stopped upon the sector 5 even for the smallest angular displacements of the said lever. For this purpose the upper face of the sector 5 can have ratchet-teeth and the lever 3 be provided with a spring-pawl; but this arrangement would compel the lever 3 to be moved at least the distance of two teeth of the sector. The arrangement I prefer and which is shown in Fig. 5 drawn to a

larger scale consists in terminating the lever 3 by a fork 3', in which is engaged the cylindrical body 4 of a piece the head of which forms a stirrup 15 embracing the sector 5. The sector 5 is fixed to the tube l by a long sleeve 16, carrying a screw-threaded lateral socket 17, in which enters a screw 22, the head of which bears upon the sector 5.

The cylindrical body 4 is screw-threaded to receive the screw 22, which is fixed on the small hand-wheel 19, which is operated to fix the lever and the sector, or vice versa. The end of the screw 22 bears upon a disk 20, provided with a stud 21, engaged in a hole made in the center of the end of the screw 22 and which centers the disk.

By turning the hand-wheel 19 from left to right the end of its screw 22 presses upon the disk 20 and the hooks of the stirrup 15 act upon the rear face of the sector, while the disk 20 presses upon the other face, so that the lever 3 is rendered quite immovable with relation to the sector 5.

The arrangement hereinbefore described which allows of regulating the relative distance apart of the two jaws $l l$ of a pair also allows of modifying the distance which separates the shaft of the boring-machine—that is to say, the shaft of the tool—from the separating-shaft in the middle of the two jaws, which is necessary in order that the machine may be adapted to rails having feet of different width. To obtain this latter adjustment, it is necessary to cause one of the jaws to leave the guide-socket x' to allow of screwing or unscrewing it upon its thread. The socket x' has at its ends a partial circular projection a' , behind which is hooked a bent finger b' , which forms part of the lever 3. By this means the device comprising the lever 3, bar 2, and jaws l is retained against the end of the socket x' and within the said socket, as shown in Fig. 2. When the lever 3 has been caused to pass beyond the end of the sector after having removed the stop-screw 23, the finger b' will have also passed beyond the end of the circular projection a' , so that the lever 3 being no longer retained the pair of jaws can be withdrawn from the socket x' , as hereinbefore stated.

Behind the pairs of jaws is arranged a kind of spring presser-foot 6, which carries at its lower part a socket 7 for guiding the boring-bit and which has a conical centering projection 8.

When it is required to use the machine, it is caused to advance above the sleeper in which it is required to bore holes. It is then placed in position on one side or other of the rail. The machine is placed so that the socket 7 engages in one of the holes made in the feet 9, arranged under the rail. By reason of the conical shape of the part 8 of the socket 7 it becomes placed in its descending movement exactly in the center of the hole in

the foot 9, and as the said socket 7 guides the descent of the tool the latter is perfectly centered.

In cases where the rail rests directly upon the sleeper the socket 7 is simply placed against the foot of the rail. In this movement the jaws come and embrace the rail. It is then only necessary to act upon the lever 3, the screw 22 of the hand-wheel 19 being loosened, in order to cause an angular displacement of the bar 2, having contrary threads on which the jaws *l* are engaged, and the latter are caused to approach one another and firmly grip the rail. The lever 3 is stopped in this position by tightening the screw 22 by means of the hand-wheel 19.

The machine being thus exactly in the position which it ought to occupy, it only remains to bore the hole. The shaft *j* *j'* being in movement, the lever *s* is depressed, which causes the fork *r* to descend. The latter, by means of the trunnions *q*, carries along the sleeve *o*, which bears upon the tool-holder and causes it to descend. The tool-holder, which is fixed to the lower part *j* of the tool-shaft, also descends, and the square upper part *j'* of the said shaft descends in the sleeve *h*, on which is keyed the pinion *c*, continuously operated by the pinion *b*, keyed upon the shaft, which receives motion from the driving-shaft. It follows that the tool always rotates and that the simple descending movement imparted by the lever *s* causes the tool to descend and bore a perfectly-centered hole in the sleeper, the direction of the hole being exactly right for the head of the bolt which is to be engaged therein to bear quite normally upon the foot of the rail or of the chair. As soon as the operator ceases to act upon the lever *s* the latter resumes its initial position, being brought back by the spiral spring *u*, and the tool rises. It then only remains to loosen the screw 22 of the hand-wheel 19 and to bring back the other lever 3 to its starting position, which causes the release of the jaws *l* *l*, and the machine is ready for a fresh operation.

At the upper part of the machine is arranged a lubricating-cup 10, in which dips a wick 11, which descends into a tube 12, forming a siphon, and which lubricates all the sliding and revolving parts of the apparatus.

Auxiliary lubricators are also provided at 13 to lubricate the bearings of the horizontal shaft *d* and two others at 14 to lubricate the mechanism for operating the jaws.

It has been stated that the power for driving the boring-machine will be applied to the shaft *g*. (Seen in Fig. 3.) As it is not important to this invention what form or kind of motor is employed for this purpose, none has been shown. It may be explained, however, that the motor may be mounted on a

car or car-truck and moved along the railway-track with the boring-machine; but this feature is not herein claimed.

Having thus described my invention, I claim—

1. A machine for boring holes in railway ties or sleepers, having a supporting-frame for the operative mechanism, the base of which is adapted to rest on the rail that is to be secured to the ties, two like pairs of rail-gripping jaws depending below the frame, guides for the said jaws, means for operating the respective pairs of jaws, a bit-holder and bit disposed at a point in a plane which is situated half-way between said pairs of jaws and with their common axes at right angles to the base of the machine, a guide for said bit and holder, and means for operating the same.

2. A machine for boring holes in railway ties or sleepers, having a frame to support the operative mechanism, a bit-holder and bit mounted in the frame, means for operating said holder and bit, a pair of jaws for gripping the track-rail and securing the machine firmly thereto, a guide for the said gripper-jaws, a bar 2 mounted rotatively in said guide and having on it steep-pitched right and left screws which engage the respective jaws for moving them, and having also a square at its outer end, a lever, the boss of which turns loosely on said square and has teeth on its outer face, a washer with teeth on its face to interlock with those on the lever, said washer fitting slidably but non-rotatively on said square, and a nut which screws onto the outer end of the bar 2 and bears on said washer.

3. A machine for boring holes in railway ties or sleepers, having a frame to support the operative parts, a bit-holder and bit upright in the frame, a guide for said holder and bit, means for operating said holder and bit, and means for securing the machine firmly to a track-rail, said means comprising a transversely-extending tubular guide for gripper-jaws, said guide being provided with a circular projection *a'*, the bar 2, rotatable in said guide and provided with right and left screws, the gripper-jaws playing in said guide and having screw-threads which engage the respective screws on said bar, the lever for operating said bar, said lever having a hooked finger *b'* which takes behind the projection *a'*, and means for securing said lever to said bar.

4. A machine for boring holes in railway ties or sleepers, having a frame to support the operative mechanism, a boring-bit and its holder, means for guiding and operating said bit and holder, and means for securing the machine firmly to a track-rail during the boring operation, said means comprising a pair of gripper-jaws for gripping the rail, a guide for said jaws, a rotatable screw-

threaded bar in said guide for operating the jaws, a lever for operating said bar, a guide-sector adjacent to said lever, and a screw device which embraces said lever and guide-sector and serves to clamp the lever to the sector at any point desired.

5. A boring-machine for the purpose specified, having a frame, a casing *a*, an upright sleeve *h* rotatable in said casing, said sleeve being square interiorly, a wheel *c* secured on said sleeve, means for driving said wheel and sleeve, a tool shaft or holder having a squared upper portion which plays in the sleeve *h*, a boring-tool carried by said

holder, a tube *m* secured at its upper end to 15 the casing *a* and alined with the sleeve *h*, said tube *m* guiding the holder and having in it slots *p*, an operating-lever, and means between said lever and the tool-holder whereby the latter may be moved longitudinally in its guide.

In witness whereof I have hereunto signed my name, this 19th day of June, 1905, in the presence of two subscribing witnesses.

ALBERT COLLET.
